CLAIM

The ornamental design for a cup-mounted holder for coffee filter paper, as shown and described.

DESCRIPTION

FIG. 1 is a front elevational view of a cup-mounted holder for coffee filter paper showing my new design; FIG. 2 is a left side elevational view thereof;

FIG. 3 is a right side elevational view thereof;

FIG. 4 is a top plan view thereof;

FIG. 5 is a bottom plan view thereof;

The rear elevational view is a mirror image of the front shown in FIG. 1.

FIG. 1

FIG. 2

FIG. 3

FIG. 4
